UNITED STATES PATENT OFFICE

91,517

DESIGN FOR A HASSOCK

John R. Ellis, Richmond, Va.

Application November 22, 1933. Serial No. 49,823

Term of patent 3½ years

To all whom it may concern:

Be it known that I, JOHN R. ELLIS, a citizen of the United States, residing at Richmond, in the county of Henrico and State of Virginia, have invented a new, original, and ornamental Design for a Hassock, of which the following is a specification, reference being had to the accompanying drawing, forming part thereof.

Figure 1 is a view in top plan of a hassock, showing my new design.

Figure 2 is a perspective view thereof.

I claim:—

The ornamental design for a hassock as shown.

JOHN R. ELLIS.
